UNITED STATES PATENT OFFICE.

FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

WAX-THREAD SEWING-MACHINE.

1,102,199.

Specification of Letters Patent. Patented June 30, 1914.

Application filed October 30, 1905. Serial No. 284,940.

To all whom it may concern:

Be it known that I, FRANK W. MERRICK, a citizen of the United States, residing at Boston, in the county of Suffolk, State of Massachusetts, have invented a certain new and useful Improvement in Wax-Thread Sewing-Machines, of which the following is a specification, reference being had therein to the accompanying drawings.

10 The invention consists, first, in devices of novel character for actuating a hooked needle and automatically regulating the length of the withdrawing stroke thereof to suit the thickness of the material or stock at 15 the place at which the new stitch is to be formed therein, so that the amount of thread that is drawn for the purposes of the said new stitch by the needle in making such stroke shall correspond properly with the 20 said thickness.

The invention consists, also, in a sewing machine having an awl-feed, and the needle arranged to work at the same side of the material as the awl, and also having in connection with the needle and needle-carrier means for causing the latter, when withdrawn from the material or stock, to be moved forward in the direction of the feed, cut of the way of the feed-movement of the 25 awl and awl-carrier. Also, in the combination with the presser of a spur projecting below the under side thereof and biting into the material or stock, so as to prevent slipping between the presser and the said material or stock during the feeding movement, and also constituting a channel-guide. Also, in a presser formed with a longitudinal opening having walls which guide the awl and needle in their movements, and an end- 30 wall which constitutes a back-stay for the awl by which the latter is supported during the feed-movement against the resistance of the material or stock to being fed. Also, in the combination with a moving feeding-arm 35 or feed-carrier, of a presser moving in unison therewith, and presser-lifting devices operating to raise the presser for the stroke of the feed-carrier in each direction, respectively.

40 In the drawings,—Figure 1 is a partly sectional front elevation of portion of a sewing machine having an embodiment of the invention applied thereto. Fig. 2, Sheet 2, is a view partly in elevation looking from the 45 left in Fig. 1, a portion of the fixed head of

the machine being removed in order to show the working parts more clearly. Fig. 3, sheet 1, is a partly sectional detail view on an enlarged scale showing the means of operating the needle-actuating rocker. Fig. 4, sheet 3, is a detail view on an enlarged scale showing the presser and related parts. Fig. 5, sheet 2, shows separately in side elevation the motion-transmitting link which serves as a connection between the needle-bar and the slotted arm of the needle-actuating rocker. Fig. 6, sheet 2, shows views of the block occupying the curved slot of the arm of the needle-actuating rocker, and of the pin serving to connect the motion-transmitting link of Fig. 5 and the said block together. Figs. 7 and 8, sheet 3, show elevations of the link which serves to connect the presser-bar with the associated rocker. Figs. 9 and 10, sheet 3, show different elevations of the locking-dog of the presser-locking mechanism of Figs. 1, 2 and 4. Fig. 11, sheet 3, shows the pivotal screw upon which the said locking-dog and the cam-actuated arm which is associated with such dog are mounted. Figs. 12 and 13, sheet 3, show different elevations of the actuating spring for the locking-dog of Figs. 9 and 10. Figs. 14 and 15, sheet 3, show different elevations of the cam-actuated arm which is 50 associated with the locking-dog of Figs. 9 and 10. Fig. 16, sheet 3, is a bottom view of the presser. Fig. 17, sheet 2, is an elevation of the needle detached, and on a larger scale than in Fig. 2. Fig. 18 is a partly sectional front elevation of portion of a sewing machine having automatic presser-foot lifting devices combined with the devices for automatically varying the length of stroke of the needle-bar. Fig. 19, is a partly sectional end elevation of the parts which are represented, in Fig. 18. Fig. 20 shows the actuator-lever of the presser-foot lifting clamp separately.

Referring, first, to Figs. 1 to 4 of the drawings,—1 is an overhanging arm forming part of the fixed frame of the machine, and 2 is a rotating shaft that is journaled in bearings within the said arm, one of such bearings being shown in dotted lines at 3 in Fig. 1. The said shaft serves in practice for the transmission of motion to various working parts in the machine. A portion of the swiveling work-supporting horn of a McKay or the like sewing machine is shown at 90, and at 901 is shewn the whirl that is 55 100 105 110

mounted in the extremity of the horn. The construction, connections, and mode of operation of the said horn and whirl may be as usual.

5 An awl is shown at 4, Figs. 1 and 2. The awl-bar carrying the said awl is represented at 41, it having V-shaped edges, as shown in Fig. 2, and being fitted to move longitudinally within V-grooved guides which are provided upon the feeding-arm 5, as indicated in Fig. 2. The awl-bar and awl are actuated from the shaft 2 through connections which are omitted from Figs. 1 and 2 in order to secure simplicity and clearness in the case of 10 the latter. Such connections are shown in Fig. 18, and comprise the disk 44 which is fast upon the shaft 2, the crank-pin 43 that is carried by the said disk, and the link 42 connecting the awl-bar with the said crank-pin, all as usual. The presser or presser-foot is shown at 6, Figs. 1, 2 and 4. At 61 is the presser-bar carrying the same, the said presser-bar being also V-edged in Figs. 1, 2 and 4, and being fitted to V-grooved guides 15 upon the feeding arm 5, as shown best in Fig. 2.

60, Fig. 2, is a spring having one end thereof in engagement with a stud 18 projecting from the presser-bar and the other end thereof in engagement with a pin 600 projecting from the feeding-arm 5. The said spring operates in connection with the presser-bar and presser to press these latter toward the work-supporting horn 90, to 35 cause the presser to hold the stock against the end of the horn.

Feed-movements are transmitted to the feeding-arm 5 from the shaft 2 by devices of any suitable and approved character.

40 Various arrangements suitable for the purpose are well known, and hence I have omitted such devices from the drawings for the sake of clearness.

45 For the support of the feeding-arm 5 the latter is constructed as a portion of a rocker which is mounted upon the arm 1. The body or rock-shaft of the said rocker is shown at 51, Fig. 1. The said body or rock-shaft is supported at its opposite ends by 50 center-screws 52, 52, Fig. 1, which are fitted to lugs 53, 53, projecting upward from the fixed frame 1. The said ends have formed therein sockets 54, 54, to receive the ends of the center-screws. The sockets are 55 incurvately tapered, and the portions of the center-screws which fit therein are conical. The center-screws may be adjusted from time to time to take up wear. They also may be operated to adjust the rocker and the feeding 60 arm in a transverse direction with relation to the direction of feed, to place the awl in the proper line with respect to the needle. In order the more effectually to restrain the feeding-arm from twisting and turning in 65 action, reduce the said twisting and turning

to an inconsiderable amount, and prevent cramping and binding, the body or rock-shaft of the rocker is made as long as is permitted by locating the lugs 53, 53, as far apart as possible upon the top of the fixed frame of the machine. Thereby ease, steadiness, and correctness of movement of the awl in feeding are secured.

7 is a needle, and 71 is the needle-bar carrying the same. The lower part of the needle-bar is supported and guided by a pair of rolls 72, 72, between which the said part of the needle-bar works, the said rolls being mounted upon the studs 73, 73, that are conveniently supported in the head of the machine. In order to hold the needle-bar from movement transversely with respect to the direction of the feed, the peripheries of the rolls 72, 72, are grooved, and the grooves thereof receive the opposite edges of the needle-bar, the said edges preferably being V-shaped and the grooves of the rolls being correspondingly formed to fit such edges. For the support and guidance of the upper part of the needle-bar the said part is slotted longitudinally at 74, and through the slot passes the stem of a flat-headed screw 75 that is applied to a lug 76 forming part of the head of the machine, the needle-bar being confined between the lug and the projecting head or flange of the screw. Movement is communicated to the needle-bar by means of a link 8, Fig. 2, having the lower end thereof pivotally engaged with the needle-bar at 81, and the upper end thereof operatively connected with an arm 9 upon one end of a rocker 10. The rocker 10 is located at the rear side of the frame 1, and corresponds essentially in construction, etc., with the rocker 51, it being mounted in practice upon center-screws that are applied to suitable portions of the frame and enter sockets in the ends of the rocker 10. The said center-screws are not shown, but correspond in character and arrangement, and in the manner of their engagement with the opposite ends of the rocker 10, with the center-screws 52, 52, which are shown in Fig. 1 in connection with the rocker 51 of the feeding-arm 5. The conical socket which is formed in one end of the rocker 10 for the reception of the corresponding center-screw is shown in Fig. 2.

110 For the actuation of the rocker 10 it is furnished, at the end thereof opposite to that at which the arm 9 is located, with a slotted or yoke-shaped arm 11, Figs. 1 and 3. The yoke or arm 11 projects from the body or rock-shaft of the rocker 10 toward the shaft 2 and receives in the opening thereof the triangular cam, or so-called triangular eccentric, 12, which is fast upon the said shaft. The said cam or triangular eccentric in its rotation with the shaft 2 produces a dwell of the rocker and of the needle-bar 115 120 125 130

and needle at each extreme of the movement which it communicates to the latter parts. To prevent the opposite members or portions of the yoke or arm 11 from springing apart from each other, and to hold both of said members or portions in contact with opposite faces of the cam, a tie-rod 111 is applied in connection with the free extremities thereof. The said extremities are 5 formed with lugs having holes therethrough. The stem of the tie-rod passes through one of such lugs, the head of the tie-rod engaging with the under side of such lug. The tie-rod is screw-threaded for a portion 10 of its length and screws into the other lug, which latter is tapped to fit the said screw-threaded portion. A lock-nut 112 prevents loss of adjustment. After a forward feed-movement of the awl, and the withdrawal 15 of the latter from the hole last formed thereby in the material or stock, the needle enters the said awl-hole in the position in which the latter is left at the end of such feed-movement, passes therethrough to receive the thread for the purposes of the next stitch-formation, and then is withdrawn. While the needle is out of the material or stock, holding its loop of thread, a movement forward in the direction of the feed 20 is communicated to the needle and needle-bar sufficient in extent to prevent the awl or awl-bar from encountering them in making the ensuing feed-stroke. For the purpose of producing the said movement, the edges 25 of the needle-bar are made cam-shaped, by forming opposite portions of such edges with corresponding inclines 721, 721, as shown in Fig. 2 which, by action against the surfaces of the rolls 72, 72, as they pass 30 such surfaces in the reciprocating movement of the needle-bar cause the needle-bar to swing in the line of the feed around the guiding screw 75. The cam-portion of the needle-bar, acting in connection with the 35 guide-rolls in the rising movement of the needle-bar, causes the lower portion of the needle-bar to swing forward a sufficient distance to secure the required clearance. In the descent of the needle-bar the cam-portion 40 co-acts with the guide-rolls to swing the needle-bar in the opposite direction into position to cause the needle to enter the awl-hole which has just been quitted by the awl, the return swing of the needle-bar being 45 timed with reference to the return stroke of the awl-bar and awl so that the needle-bar and needle shall not be carried against such parts in the course of such swing. 50 For the purpose of enabling the throw of 55 the needle-bar and needle to be varied, the point of connection between the link 8 and the arm 9 of the rocker 10 is made adjustable toward and from the axis of motion of the said rocker, in order that thereby the 60 distance through which the said point of connection oscillates with the said arm may be made greater or less, as may be required. It will be clear that, the greater the distance from the axis of motion of the rocker 10 to the said point of connection, the greater will be the distance through which the point of connection will oscillate and the greater will be the extent of the movement which is transmitted through the link 8 to the needle-bar and needle, and that in proportion as the said distance is increased or decreased the extent of the movement of the needle-bar and needle will increase or decrease, as the case may be. For the purposes of the adjustment the arm 9 is slotted in the direction of the length thereof as at 91, Fig. 2, and a block 92, Fig. 6, is fitted within the slot 91, the said block having a hole 93 therethrough receiving a pin 82, the ends of which project at opposite sides of the block. The link 8 is forked at its upper end, as shown in Fig. 5, and receives in the space between the branches 83, 84, of the fork the arm 9 of the rocker 10 and the block 92 occupying the slot 91 in such arm, the said branches being formed with eyes or sockets within which the opposite ends of the pin 82 fit. The eye or socket of branch 83 is split and furnished with a clamping screw, as indicated in Figs. 2 and 5, by means of which to tighten the same upon the corresponding end of the pin 82 so as to hold the pin securely in place. In making the adjustment by which the throw of the needle-bar and needle is varied, the block 92 shifts along the slot 91 toward or from the axis of motion of the rocker 10. In order that the needle shall at all times descend to the same point and that the difference in the extent of the movement of the needle shall only vary the point which is reached by the needle at the end of its withdrawing or rising movement, the slot 91 is formed with a curvature that is concentric, in the lowest position of the said arm, with the point 81 of the pivotal connection between the link 8 and the needle-bar 71. 75 To enable the adjustment of the point of connection between the motion-transmitting link 8 and the arm 9 of rocker 10 to be effected automatically to suit the thickness of the stock which is being stitched, and variations in such thickness, the upper end of the link 8 is connected with the presser-bar by intermediate devices serving to determine the position of the said point of connection in accordance with that of the presser, the said devices comprising a link 15, a rocker 16 having arms 161 and 162 and a second link 17. The link 15 engages by one end thereof with the pin 82, and by the other end thereof with the pin 163 which is carried by the arm 161 of the rocker 16, and it serves to transmit movement from the said rocker to the upper end of link 8, to occasion 80 85 90 95 100 105 110 115 120 125 130

the shift of the point of connection between the said link and the arm 9, farther from or nearer to the axis of motion of the rocker 10. One end of the link 15 fits in the notch 85, Fig. 5, that is formed in the branch 84 of the link 8, the pin 82 passing through the eye or hole that is formed in this end of the link 15. The opposite end of the link 15 fits between the two branches of the forked upper end of the arm 161 of the rocker 16, as indicated in Fig. 1, and the pin 163, which last is held in sockets in the said branches, passes through the eye or hole in this end of the said link. For the purpose of enabling the pin 163 to be secured in place within the sockets, the latter are split and are furnished with clamping screws 164, 164, by means of which to contract the same tightly upon the pin. The rocker 16 is supported by center-screws 166, 166, Fig. 1, which are applied to lugs 167, 167, projecting from the head of the machine-frame, the rocker being thereby supported in place. The body or rock-shaft of the said rocker is formed at its opposite ends with tapering or conical sockets to receive the conical ends of the said center-screws. One of the said sockets is shown at 168 in Figs. 2 and 4. The link 17 connects the arm 162 of the rocker 16 with the presser-bar 61, and serves to transmit movement from the latter to the rocker. Its upper end is formed with a socket 171, Figs. 7 and 8, fitting the head of the screw 172 that is carried by the arm 162 of the rocker. To enable the stud and socket to be fitted together so as to obviate play, and also to enable wear to be compensated for, the head of the stud is formed tapering, being largest at its outer end, and the socket 171 is formed with a corresponding bore. The lower end of the link 17 is formed with a split socket 173, see Figs. 7 and 8, provided with a clamping screw 174. Within the said split socket is placed the bushing 175 having a tapering bore to fit the tapering body of the stud 18, Figs. 1, 2 and 4, which is applied to the presser-bar 61. At the small end of the conical portion of the stud 18 the latter is screw-threaded and receives the nuts 176 by means of which the lower end of the link 17 is held in place upon the stud. By means of the said nuts the bushing may be caused to fit properly upon the stud 18, and looseness due to wear may be taken up. Through the connections described the distance of the connecting-pin 82 from the axis of motion of the rocker 10 is automatically controlled by the position of the presser. When the presser is raised to a higher position in consequence of the passage of a portion of stock of increased thickness beneath the same, the connecting pin 82 will be moved farther away from the axis of motion of the rocker 10, so that the upward swing of the arm 9 will raise the

needle-bar and needle a greater distance than before. When the presser is permitted to move toward the work-support by the entrance of a portion of stock of less thickness beneath the same, the connecting-pin 82 will be caused to approach the axis of motion of the rocker 10, thus reducing the extent of the upward stroke of the needle-bar and needle. Thereby the length of the withdrawing stroke of the needle is automatically controlled to suit the thickness of the stock, so as to cause loops of needle thread to be drawn of proper lengths for the successive stitches, and variations in the thickness of the stock are compensated for. 80

In order to enable the ratio between the length of needle-stroke and the thickness of the stock to be varied when required, provision is made for a relative shift or adjustment of the point of connection between the link 8 and arm 9 to attain the ratio that is desired. This relative shift or adjustment is accomplished by causing the said point of connection to occupy a position nearer to or farther from the axis of motion of the rocker 10 for a given position of the presser. To this end, the stem of stud 18 is fitted in a slot 62, Figs. 2 and 4, formed in the presser-bar 61 and extending longitudinally of the latter, the said slot 95 providing for adjustment of the stud in the direction of the length of the presser-bar, and the stud being secured in adjusted position by means of a nut 181. When the stud 18 is adjusted in the direction of the length 100 of the slot 62 it produces through the intermediate connections a corresponding adjustment of the point of connection between the upper end of the link 8 and the arm 9, either toward or from the axis of motion of 105 the rocker 10 according as the stud 18 is adjusted from the work-support or toward the latter. This occasions a proportionate difference in the length of the needle-strokes corresponding with a given position of the 110 presser.

Figs. 1 and 2 show an automatic locking mechanism combined with the presser and the devices for varying the length of stroke of the needle. Fig. 4 shows the said mechanism separately on an enlarged scale. It comprises a sector 169, Figs. 1, 2 and 4, forming part of or connected with the rocker 16 and moving in unison therewith, the dog 19, shown separately in Figs. 9 and 10, which is mounted upon a pivot 20, shown separately in Fig. 11, and provided with an eccentric portion 191 for engagement with the peripheral portion of the said sector 169, and a spring 21 by means of which the 120 said dog 19 is turned or swung around the said pivot so as to cause its eccentric portion to engage with the sector. The spring 21 is shown separately in Figs. 12 and 13, and in place in the machine in Figs. 1, 2 and 4. 130

It is formed with a coil that surrounds and is concentric with the pivot 20, one of the extremities of the spring being engaged with the fixed head of the frame as indicated in Fig. 1, and the other thereof with a pin 192 projecting laterally from the dog 19. The spring acts with a tendency to turn the dog so as to cause the eccentric engaging portion 191 of the latter to take hold of the periphery of the sector 169 and thereby lock the rocker 16, presser-bar, and presser. For the purpose of intermittently unlocking the rocker 16 to temporarily release the presser, the periphery of the disk 22 on the shaft 2 is formed with a prominence or cam 221, and in connection with the dog 19 and arm 23 is provided. The said arm 23 is shown separately in Figs. 14 and 15, and in place in the machine in Figs. 1, 2 and 4. It is mounted to turn upon the body of the pivot-screw 20, and comprises essentially opposite side-portions 231, 231, receiving between them the body of the dog 19 and having eyes or holes 232, 232, to receive and fit the body of the pivot-screw 20, and a cross-web 233 connecting the said side-portions 231, 231. The dog 19 is furnished with an adjustable contact-piece which is constituted by a screw 193, the latter being furnished with a lock-nut 194 to prevent loss of the adjustment thereof. The acting end of the said contact-screw is designed to engage with the cross-web 233. In the rotation of the shaft 2, the prominent portion 221 of the periphery of the disk 22 presses against the arm 23, and operates the said arm so as, by the engagement of the cross-web 233 with the contact-screw 193, to press back the dog 19, turning the said dog so as to unclamp the sector and unlock the presser. The locking devices are operated to hold the presser locked at all times except during the return movement of the feeding arm 5 after the feed-movement of the said arm.

At 601 is shown a hand-lever for use in moving the presser-bar and presser manually when it is desired to withdraw the presser from proximity to the horn 90, as for the purpose of permitting stock to be introduced between the presser and horn, or removed. This hand-lever 601, of which the outer portion or extremity is broken away in Figs. 1, 2 and 4, is formed with a hub-portion 602, Fig. 1, which is sleeved upon the body or rock-shaft of the rocker 16, as shown in the said figure, whereby the hand-lever is supported. A slot 603 is formed through the main portion of the said hand-lever, concentric with the body or rock-shaft of the rocker 16, and through the said slot passes the stem of a screw 604, the threaded stem of which enters a screw-threaded hole that is tapped in the sector 169 of the rocker 16. The body of the hand-lever 601 is confined between the said sector and the radially-

projecting rim or flange of the head of the screw 604. The hand-lever 601 is acted upon by a contracting spiral spring 605 having one end thereof engaged with a projection on the side of the hand-lever, and the other end thereof engaged with a hook or the like, as at 606, upon the fixed head of the machine. By means of the said spring the hand-lever is held normally in the position in which it is represented in the drawings. Pressure applied to the outwardly-projecting portion of the hand-lever, operating to turn the said hand-lever upon its support, will carry the wall at the inner end of the slot 603 against the stem of the screw 604, and will operate to turn the rocker 16 and withdraw the presser. In order to unlock the presser so as to permit the said withdrawal to be effected, the hand-lever 601 has pivotally connected thereto the lower end of a bar 607, the upper end of which is slotted at 608, as shown best in Fig. 4. The said slot receives a pin 609 projecting from an extension 234 of the arm 23. This slot permits the arm 23 to move under the influence of the cam or projection 221 of disk 22 and of spring 21, without interference. When, however, the hand-lever is turned as described above to effect the withdrawal of the presser, the endwise movement of the bar 607 carries an end-wall of the slot 608 against the pin 609, and during the remainder of the movement of the hand-lever the arm 23 is caused to turn so as, by the contact of its cross-web 233 with the contact-screw 193 of the locking arm 19, to move the said arm so as to unlock the sector 169 and thereby free the presser. This unlocking precedes contact of the wall at the inner end of slot 603 with the stem of screw 604.

The employment of a locking mechanism as in Figs. 1, 2, and 4, permits a light presser-spring to be used. In some cases I contemplate the employment of a presser-spring which is powerful enough to resist the tendency of the material or stock which is being operated upon to lift as the awl is pulled therefrom and when the rise of the needle occurs. In such cases I employ automatic presser-lifting mechanism operating to lift the presser at the beginning of the feed and to hold it lifted while the forward or feeding action of the awl and presser takes place, so as to facilitate the feeding of the material or stock, then drop the presser and permit it to remain down during the rise of the awl, then raise the presser during the return or recovery movement of the awl and presser, and then drop the presser and permit it to remain down while the awl descends. A form of the said presser-lifting mechanism is shown in Figs. 18 and 19. In such figures, 64 is a block which is recessed to fit upon the presser-bar in a manner per-

mitting relative movement of the block and presser-bar in the direction of the length of the latter. The block is shaped to fit against one edge of the presser-bar, and has side-
5 portions receiving the presser-bar between them and projecting beyond the opposite edge of the presser-bar. The said block rests normally upon ledges or shoulders 641, 641, in connection with the feeding-arm 5, the said ledges or shoulders being provided with leather pads 6411, 6411, to cushion the blow of the block 64 in descending. At 642 is a dog or clamping-lever which occupies a position adjacent the second edge of the
10 presser-bar, between the opposite side-ports or cheeks of the block 64, it being pivotally mounted at one end thereof upon a pivotal screw 643 which passes through the side-ports or cheeks and the said dog or
15 clamping-lever and is secured in place in the former. The dog or clamping-lever is formed at its pivoted end with a cam or eccentric portion to make contact with the proximate edge of the presser-bar. When
20 such portion is pressed firmly against such edge by a forward turning movement of the lever, the presser-bar is clamped between the block and clamping-lever.
25 At 644 is an actuator-lever for the dog or clamping-lever 642, the acting end of the said actuator-lever 644 being entered between the side-ports or cheeks of the block 64, and being pivotally mounted upon a pivotal screw 645 which is passed through
30 the said side-ports or cheeks and the said end of the actuator-lever, and secured in place in the former. The acting end of the actuator-lever 644 is formed with an eccentric or cam-portion which makes contact
35 with the dog or clamping-lever at or near its free extremity. When such portion is caused to bear firmly against the said dog or clamping-lever, the latter is operated to clamp the presser-bar against the opposing
40 portion of the block 64. For the transmission of power to the actuator-lever, to operate the clamp, the actuator-lever has pivotally joined to the free extremity thereof one end of a connecting-link 646, the other
45 end of which is similarly joined to a downwardly-extending arm 65 of a rocker 651 which is mounted upon the upper portion of the fixed frame of the machine. The rock-shaft of the said rocker is of considerable
50 length, for the reasons applying in the case of the rock-shaft 51 of the rocker of the feeding-arm 5, and is mounted at its ends upon the conical ends of center-screws 66, 66, which are applied to lugs 661, 661, projecting from the head of the machine, and the arm 1 near the opposite end thereof, respectively. The rocker 651 is operated by means of a second arm 652 of the rocker 651, extending upward therefrom
55 and provided with a stud 653 with

which is engaged the strap 67 of an eccentric 68 fast upon the shaft 2. By the rotation of the said shaft and eccentric oscillating motion is transmitted to the rocker 631 through the strap and its connection with arm 632. To permit the extent of this motion to be adjusted at need, the stud 633 is adjusted radially along the arm 632, toward or from the axis of motion of the rocker. This adjustment is provided for by setting the arm 632 lengthwise for the reception of the base-portion of the stud 633, and securing the stud at the desired point in the length of the slot by means of a nut 634. The rocking motion of the rocker 631 carries the point of pivotal connection between the downwardly-extending arm 65 thereof and the connecting-link 646 to opposite sides, alternately, of a straight line connecting the center of the rocker end and that of the pivotal connection between the lower end of connecting-link 646 and the actuator-lever 644. When the point of pivotal connection first-mentioned is in the said straight line, the distance between the axis of rocker 631 and the point of connection between connecting-link 646 and actuator-lever 644 is the greatest. At such time, the block 64 rests upon the cushions 641, 641, upon the shoulders 641, 641, and the actuator-lever 644 occupies a position in which the pressure of its eccentric or cam-portion against the dog or clamping-lever is relaxed. Consequentially the hold of the clamp upon the presser-bar is released, and the presser is held by the action of the presser-spring in contact with the material or stock beneath it, or with the work-support in the absence of such material or stock. When the said point of pivotal connection is carried by the movement of the rocker to one side or the other of the said straight line between centers, the bending of the joint or knuckle which is formed by arm 65 and connecting-link 646 causes the outer or free extremity of the actuator-lever 644 to be drawn upward, first turning the said lever 644 upon its pivot upon the block 64 and causing it to turn the dog or clamping-lever 642 upon the pivot thereof against the presser-bar until the latter has been tightly grasped by the clamp, after which the further bending of the joint or knuckle operates to raise the clamp, presser-bar, and presser until the presser is lifted from the material or stock. This clamping of the presser-bar, and lifting action, occur in the movement of the rocker in each direction. In the subsequent return movement of the knuckle or joint toward the said straight line between centers, the clamp, presser-bar, and presser are lowered descending in unison with the presser-spring bearing upon the material or stock, or the block 64 rests upon the cushions 641, 641, as indicated in Fig. 2, in either case,

the straightening of the knuckle or joint then operates to turn the actuator-lever 644 upon its pivotal connection with block 64 so as to relieve the pressure acting to hold the clamping-lever 642 in engagement with the presser-bar, and in consequence of such relief the hold of the clamp upon the presser-bar is relaxed. This relaxation permits the presser and presser-bar to accommodate its position to the thickness of the material or stock independently of the block, which latter comes to rest upon the cushions 6411, 6411. As the knuckle or joint passes the line extending from center to center, the actuator-lever is turned upon its point of pivotal connection at 645 with the block 64 until the clamping-lever 642 has again been closed against the presser-bar, whereupon the presser-bar and presser are again lifted, to be subsequently lowered again, and so on. The extent of the lift of the clamp is slight, being only sufficient to raise the presser to a small height above the upper surface of the material or stock. This fact, and the further fact that the clamp automatically operates to lift the presser a uniform extent every time, regardless of the height of the upper surface of the material or stock, and of variations in such height, enable the actual lifting to be effected within a relatively small portion of the cycle of stitch-forming and feeding operations, and within the same relative portion of such cycle whatever the height of the material.

The presser 6 is furnished with a spur 649, which is arranged to project below the under side of the presser and is intended to bite into the stock so as to prevent slipping between the presser and the stock during the feeding movement. The said spur is designed, also, to enter the channel or groove that is formed in the stock for the reception of the interchained portions of the stitches, and thus to constitute a guide for securing the proper placing of the said channel or groove in the path of the awl and needle. In order to prevent the spur from being lifted out of the channel or groove by adjacent prominent portions of the stock passing under the presser and acting to raise the latter, the spur is mounted with capacity for independent movement with respect to the presser and is spring-actuated to cause it to remain within the channel or groove and in engagement with the stock notwithstanding slight elevation of the presser occasioned as stated. The said spur is shown formed upon the lower extremity of an arm which is mounted upon the side of the presser-shank by means of a pivot-pin or stud 659 projecting from the presser. The spring by which the said arm is actuated is shown at 669, it being a contracting spiral spring having one extremity thereof engaged with a pin 679 projecting from the upper part

of the shank of the presser and the other end thereof engaged with a pin 689 projecting from the pivoted arm. For the purpose of determining the limit of the movement of the spur 649 under the action of the spring 669, a pin or stud 690 is applied to the shank of the presser, it projecting therefrom into position for engagement with the pivoted arm.

The presser is formed with a longitudinal opening 600* which is shown best in Fig. 16, Sheet 3. The awl and needle work through this opening, the walls of which serve to guide the awl and needle in their movements. The wall at the closed end of the said opening also constitutes a back-stay for the awl by which the latter is supported during the feed movement against the resistance of the stock to being fed, and thereby is prevented from springing in consequence of the strain which it experiences in feeding the stock.

In order to enable a cast-off to be dispensed with and the machine to be correspondingly simplified in its construction, I employ a straight hooked needle 7 having within itself means for taking and shedding the loop in forming the stitch. The said needle is shown best in Figs. 2, 17, and 19. It has the open eye and the hook or barb thereof faced in the direction toward which the stock is moved in being fed by the machine. It will be clear that after the said needle has been caused to pass through the stock so as to project at the opposite side of the latter, and the thread has been laid by the whirl 901, or equivalent looper, around the needle and in the open eye thereof, the said thread will be drawn in the shape of a loop through the stock by the needle in its returning movement, substantially as heretofore. In order that in the said returning movement of the needle the loop which is being drawn thereby may not slip from around the needle over the point thereof, I provide the needle with a thread-detent by means of which the portion of the loop which extends around the needle from one side of the eye thereof is prevented from slipping over and from the point. Such a detent is shown at 701 in the form of a spiral flange extending around the needle between the open eye and the needle-point, the said flange being constituted by one wall of a groove beginning on one side of the needle at the open eye and terminating on the opposite side of the needle closely adjacent or at the point. It will be clear that the open eye and hook or barb of the needle, in consequence of facing in the direction toward which the stock is moved in being fed by the machine, will be shielded from the closed end or bight and opposite side-portions of a loop of thread extending from the last completed stitch in the stock to and

- around the needle and strained about the latter by the advance of the stock in being fed. Consequently, after the needle has been moved endwise to and through the stock to receive the thread for a fresh loop, and thereby has been moved within the old loop so as to completely disengage the hook or barb from the said loop and bring the needle-stem into the latter, the hook or barb will entirely clear the said old loop in the returning movement of the needle with the new loop, so that the old loop will shed readily and freely from the needle over the said new loop.
- 15 I claim as my invention:—
1. The combination with the needle, the needle-bar, the needle-actuating rocker, and the link directly connecting the needle-bar with the said rocker, of means operating to shift the point of connection of the said link with the said rocker toward and from the axis of motion of the rocker to vary the stroke of the needle to suit the thickness of the stock which is being stitched.
  2. The combination with the needle, needle-bar, and presser, of the vibrating actuator-arm, the link in direct connection at its one end with the needle-bar and at the other end with said actuator-arm and serving to transmit motion from the actuator-arm to the needle-bar, and connections intermediate the presser and the link operating to shift the point of connection between such link and the actuator-arm toward and from the axis of motion of the latter as the presser varies its position.
  3. The combination with the needle, needle-bar, and presser, of the vibrating actuator-arm, the motion-transmitting link in direct connection at its one end with the needle-bar and at its other end with said actuator-arm, and a rocker in operative connection with the presser and the said link and serving to shift the point of connection between such link and the said vibrating actuator-arm as the presser varies its position.
  4. In a sewing machine, in combination, a movable feed-carrier, an awl and awl-carrier mounted thereon, a presser mounted on said feed-carrier and accompanying the same in its feed-movements, a needle and needle-carrier located at the same side of the work, means to shift the needle and needle-carrier out of the path of the awl and awl-carrier in the feed-movement, and means to lift the said presser during the advancing movement of the feed-carrier, awl, awl-carrier, and presser.
  5. In a sewing machine, in combination, a movable feed-carrier, an awl and awl-carrier mounted thereon, a presser mounted on said feed-carrier and accompanying the same in its feed-movements, a needle and needle-carrier located at the same side of the work, means to shift the needle and needle-carrier out of the path of the awl and awl-carrier in the feed-movement, and means to lift the said presser during the feed and return movements of the feed-carrier, awl, awl-carrier, and presser.
  6. In a sewing machine, the feeding-arm, the feeding-devices carried thereby, and the presser accompanying the said devices in the feed-movements and provided with a work-pressing surface and with a spur projecting below the said surface and biting into the material or stock so as to prevent slipping between the presser and said material or stock during the feeding movement, and also constituting a channel-guide.
  7. In a sewing machine, the feeding-arm, the feeding-devices carried thereby, the presser accompanying the said devices in the feed-movements, and the spring-actuated spur projecting below the under side of the presser and biting into the material or stock so as to prevent slipping between the presser and said material and stock during the feeding movement, and also constituting a channel-guide.
  8. In a sewing machine, the combination with the awl and needle and means for producing feed-movements of the awl, of the presser formed with a longitudinal opening within which the awl and needle work, and having an end-wall which constitutes a back-stay for the awl by which the latter is supported during the feed-movement against the resistance of the material or stock to being fed.
  9. In combination with the needle, and needle-bar, of the rocker having opposite bearings in the line of the axis thereof, means to actuate the said rocker, a link directly connecting the needle-bar with the said rocker, and means operating to shift the point of connection of the said link with the said rocker toward and from the axis of motion of the rocker to vary the stroke of the needle to suit the thickness of the stock which is being stitched.
  10. The combination with a feed-carrier; means for operating the same for the purposes of the feed, and feeding means in connection with said feed-carrier, of a presser moving in unison with the said feed-carrier, and presser-lifting devices operating to raise the presser for the stroke of the feed-carrier in each direction, respectively.
  11. The combination with a feed-carrier, and means for operating the same for the purposes of the feed, of a presser moving in unison with the said feed-carrier, and presser-lifting devices operating automatically to raise the said presser to a uniform distance above the upper surface of the material or stock for the stroke of the feed-carrier in each direction, respectively.
  12. The combination with a feed-carrier,

means for operating the same for the purposes of the feed, and feeding-means in connection with the said feed-carrier, of a presser moving in unison with the said feed-carrier, and lifting devices embracing a double-acting toggle by which the presser is raised for the stroke of the feed-carrier in each direction, respectively.

13. The combination with a presser, of lifting devices therefor embracing a double-acting toggle and means for operating said toggle to raise the presser twice in each to-and-fro movement of the said toggle.

14. The combination with a presser, of a lifting-clamp, and a double-acting toggle operating the said clamp and means for actuating said toggle to raise the presser twice

in each to-and-fro movement of the said toggle.

15. The combination with the feeding-arm, the reciprocatory bar supported thereby and provided with the feeding implement which penetrates the stock, of a presser also supported by the said feeding-arm, and a double-acting toggle operating 20 to raise the said presser for the stroke of the feeding-arm in each direction, respectively.

In testimony whereof I affix my signature in presence of two witnesses.

FRANK W. MERRICK.
